(57) **CLAIM**

The ornamental design for a drum cartridge with toner container, as shown and described.

DESCRIPTION

FIG. 1 is a front, right side, top perspective view of a drum cartridge with toner container showing my new design; FIG. 2 is a rear, left side, bottom perspective view thereof; FIG. 3 is a front elevational view thereof; FIG. 4 is a rear elevational view thereof; FIG. 5 is a left side view thereof; FIG. 6 is a right side view thereof; FIG. 7 is a top plan view thereof; FIG. 8 is a bottom plan view thereof; FIG. 9 is an enlarged left side view thereof, rotated at a 90-degree angle; FIG. 10 is an enlarged right side view thereof, rotated at a 90-degree angle; and,

FIG. 11 is an enlarged cross-sectional view thereof, taken along 11-11 of FIG. 3 with the internal structure omitted and rotated at a 90-degree angle.

The broken lines shown in the drawings illustrate portions of the drum cartridge with toner container that form no part of the claimed design.
